Primary Examiner—Cathron C Brooks*Assistant Examiner*—Deanna Fluegeman(74) *Attorney, Agent, or Firm*—Banner & Witcoff, Ltd.(57) **CLAIM**

The ornamental design for an icon for a display screen, as shown and described.

DESCRIPTION

The FIGURE is a front view of an icon for a display screen showing our new design.

The broken line showing of the portion of a display screen illustrates unclaimed environmental structure and forms no part of the claimed design.
